UNITED STATES PATENT OFFICE.

ROBERT W. LINDSAY, OF MIDDLETOWN, NEW YORK.

DESIGN FOR A GAME-BOARD.

SPECIFICATION forming part of Design No. 28,674, dated May 17, 1898.

Application filed March 12, 1898. Serial No. 673,664. Term of patent 3½ years.

To all whom it may concern:

Be it known that I, ROBERT W. LINDSAY, a citizen of the United States of America, and a resident of the city of Middletown, in the county of Orange and State of New York, have invented and produced a new and original Design for a Game-Board, of which the following is a specification.

The design consists of the novel ornamentation for a game-board, as hereinafter set forth, and illustrated in the accompanying drawings, wherein—

Figure 1 is a plan view of a game-board made in accordance with my invention, and Fig. 2 is a section taken on the line 2 2 in Fig. 1 and looking toward the top of the sheet.

The drawings show a board of an equilateral rectangular outline, having upon its surface a series of straight lines so arranged at right angles to each other and to the outer edges of the board as to form an angular path at each corner of the board, one end of each of such paths being closed and the other being open and being connected in a more or less intricate manner with each other and

with a number of square spaces (nine in number) located centrally upon the surface of the board and each having an opening at one side, and a depression in the board located centrally of each of said square spaces. The nine spaces are arranged in three rows of three squares each, separated by four straight intersecting passages.

A designates the border of the board.

B B B represent the angular paths at the corners of the board.

C C, &c., represent the nine square spaces, and D, &c., represent the straight intersecting passages separating the said square spaces.

E E, &c., represent the central depressions within the square spaces.

I claim as my invention—

The design for a game-board, substantially as herein shown and described.

Signed by me, at the city of Middletown, New York, this 7th day of March, 1898.

ROBERT W. LINDSAY.
